US0D1049850S

(12) **United States Design Patent** (10) Patent No.: **US D1,049,850 S**
(45) Date of Patent: ** Nov. 5, 2024

(54) **CONTAINER LID**(71) Applicant: **Inno-Pak, LLC**, Delaware, OH (US)(72) Inventor: **Jonathan D. Sill**, Delaware, OH (US)(73) Assignee: **Inno-Pak, LLC**, Delaware, OH (US)(**) Term: **15 Years**(21) Appl. No.: **29/843,274**(22) Filed: **Jun. 20, 2022****Related U.S. Application Data**

(62) Division of application No. 29/656,462, filed on Jul. 12, 2018, now Pat. No. Des. 955,807.

(51) LOC (14) Cl. **07-99**

Ryan K. Simmons

(57) **CLAIM**

The ornamental design for a container lid, as shown and described.

DESCRIPTION

FIG. 1 is a top perspective view of a first embodiment of a container lid, showing my new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top perspective view of a second embodiment of a container lid, showing my new design;

FIG. 9 is a top plan view thereof;

FIG. 10 is a bottom plan view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top perspective view of a third embodiment of a container lid, showing my new design;

FIG. 16 is a top plan view thereof;

FIG. 17 is a bottom plan view thereof;

FIG. 18 is a front elevation view thereof;

FIG. 19 is a rear elevation view thereof;

FIG. 20 is a left side elevation view thereof;

FIG. 21 is a right side elevation view thereof;

FIG. 22 is a top perspective view of a fourth embodiment of a container lid, showing my new design;

FIG. 23 is a top plan view thereof;

FIG. 24 is a bottom plan view thereof;

FIG. 25 is a front elevation view thereof;

FIG. 26 is a rear elevation view thereof;

FIG. 27 is a left side elevation view thereof;

FIG. 28 is a right side elevation view thereof;

FIG. 29 is a top perspective view of a fifth embodiment of a container lid, showing my new design;

FIG. 30 is a top plan view thereof;

FIG. 31 is a bottom plan view thereof;

FIG. 32 is a front elevation view thereof;

FIG. 33 is a rear elevation view thereof;

FIG. 34 is a left side elevation view thereof;

FIG. 35 is a right side elevation view thereof;

FIG. 36 is a top perspective view of a sixth embodiment of a container lid, showing my new design;

FIG. 37 is a top plan view thereof;
FIG. 38 is a bottom plan view thereof;
FIG. 39 is a front elevation view thereof;
FIG. 40 is a rear elevation view thereof;
FIG. 41 is a left side elevation view thereof;
FIG. 42 is a right side elevation view thereof;
FIG. 43 is a top perspective view of a seventh embodiment
of a container lid, showing my new design;
FIG. 44 is a top plan view thereof;
FIG. 45 is a bottom plan view thereof;
FIG. 46 is a front elevation view thereof;
FIG. 47 is a rear elevation view thereof;
FIG. 48 is a left side elevation view thereof; and,
FIG. 49 is a right side elevation view thereof.
The broken lines are shown for the purpose of illustrating
parts of the article that form no part of the claimed design.
